UNITED STATES PATENT OFFICE

JOHN S. STOKES, OF HUNTINGDON VALLEY, PENNSYLVANIA, ASSIGNOR TO STOKES AND SMITH COMPANY, OF PHILADELPHIA, PENNSYLVANIA, A CORPORATION OF PENNSYLVANIA

METHOD OF PACKING AND WRAPPING ARTICLES

Application filed October 11, 1927, Serial No. 225,472. Renewed October 21, 1930.

My invention relates to the art of packing and wrapping, articles, packages, cartons, and the like hereinafter generically referred to as "articles".

In accordance with my invention, a wrapper is brought into adhesive engagement with a container or the component parts thereof before, during, or after the forming of the container or assembly of its separate elements 10 on or around an article to be totally enclosed or packed, and complete joinder or union of container walls is effected during a wrapping operation.

More particularly, in accordance with my 15 invention, a container or enclosing casing is formed or constructed by assembling a plurality of separate container-forming components preferably two complementary structures on or about an article in container-forming position to enclose said article and to the assembled container there is applied a wrapper or the like, preferably consisting of a single piece, having thereon an adhesive coating, preferably fluid in character.

Further in accordance with my invention, 25 the wrapper is provided with a plurality of reinforcing elements or tabs, suitably disposed and of such shape and size as to effect joinder of adjacent, free edges of the walls of the assembled container throughout their length to seal the container or enclosing structure and to strengthen or reinforce the sealed container at the lines of joinder of its walls.

Further and more particularly, in accordance 30 with my invention the tabs and container are moisture-proof and the coated wrapper is disposed wholly exteriorly of the container permitting the interior thereof to be rendered waterproof, as by lining it with metal foil or coating it with paraffin or the like, without loss of adhesion between the wrapper and the container.

My invention resides in a wrapper, made 45 of one piece or a plurality of components suitably connected as by adhesive to form a composite wrapper, having disposed thereon reinforcing or tab strips to strengthen the junction of abutting walls constituting edges of a closed container.

My invention resides in a method of wrap-

ping and packing an article, package or equivalent as hereinafter described and claimed.

For an illustration of some of the various modes of practising my invention, reference is to be had to the accompanying drawings 55 in which:

Fig. 1 is a perspective view of a container component or element.

Fig. 2 is a perspective view of a package disposed on the container element of Fig. 1. 60

Fig. 3 is a perspective view of the package and container element of Fig. 1 in a later stage of progress.

Fig. 4 is a perspective view of the package and container element of Fig. 2 and a second 65 container element positioned thereover.

Fig. 5 is a perspective view in which the second container element of Fig. 4 is in its final position.

Fig. 6 is a perspective view of a wrapper 70 having tab strips applied thereto.

Fig. 7 is a perspective view of the tabbed wrapper at a later stage in which the tabbed strips are cut or notched.

Fig. 8 is a perspective view of the tabbed 75 wrapper in register with the assembled or formed container.

Figs. 9 to 13 inclusive, represent, respectively, in perspective, the successive stages of the wrapping operation.

Fig. 14 is a perspective view of a wrapper 80 in which the disposition of the tab strips is modified.

Fig. 14a is a further modified form of a 85 tabbed wrapper.

Fig. 15 is a perspective view of the tabbed wrapper of Fig. 14 at a later stage in which the tab strips are cut or notched.

Fig. 16 is a perspective view of the modified tabbed wrapper in register with the assembled or formed container of Fig. 5. 90

Figs. 17 to 22 inclusive, represent respectively, in perspective, the successive stages of the final wrapping operation.

The container or shell, in accordance with 95 my invention, is made preferably of two pieces of suitable material, as cardboard, scored or creased across their shorter dimensions, one of which, 1, is disclosed in Fig. 1. The length and width of the base section 1a 100

should equal or closely approximate the corresponding dimensions of the article or package A to be packed. Similarly the height and length of the side flap section 1b should 5 equal or closely approximate the thickness and length of the package. In the event that the articles to be packed are readily deformable in character, as in the case of bags containing cereals, soap powders, etc., the above 10 dimensions of the cardboard, container element or component should correspond to the exterior dimensions of a liner of relatively stiff material, as cardboard, disposed wholly or partially about the deformable article to 15 maintain it in package form.

Similarly, the base section 2a and end flap sections 2b of the second container component 2, Fig. 4, should closely correspond in length and width to the upper face and ends respectively of the package A. The protective shell may be formed or assembled about the package by bringing one or more of the sections of either or both of the cardboard pieces into contact with the corresponding face or 25 faces of the article, package or a liner disposed about the same, and successively, in any sequence, or simultaneously, effecting engagement between the package or liner and the remaining sections of the container to 30 complete the packing operation. Certain or all of the components may be held temporarily in position by pressure exerted thereon as hereinafter more fully explained.

Preferably, the packages are moved manually, or by automatic mechanism, individually and in succession, from a magazine or other source of supply, and in turn are deposited or positioned on a cardboard piece, for example, a lower container element 1, 40 which is preferably moved manually or otherwise from a stack before, or after, registration of the package therewith.

During movement of the package and container element 1 along a defined path to a 45 wrapping station or at the wrapping station, the side flaps 1b are folded into engagement with the sides of the package and immediately thereafter or substantially simultaneously therewith, the remaining container element 2 is moved at right angles to the path of movement of and in superimposed relation to the first element and package with the scores of the respective elements at right angles to each other, the end flaps 2b thereof 50 are folded down to completely enclose package A without overlapping of the cardboard sections. Each article, in turn, is packed in the same manner and preferably, before each reaches the wholly packed stage shown in 55 Fig. 5 one or more other articles have passed through in succession earlier stages of the packing operation above described. By making the shell in two rectangular pieces as disclosed a minimum amount of cardboard or 60 like material and labor is required and no 65

corner-cutting operation is necessary. Instead of as shown, the container elements may each consist of several pieces held together by adhesive coated strips or tabs, or the unformed container may be a single piece 70 in which corner-cutting is necessary. In each of these instances, there is likewise no overlapping of the walls of the assembled or formed container.

The wrapper 3 is, preferably, as shown, a 75 single piece of paper or other suitable material which has been previously shaped or cut to a desired configuration or it may be a composite wrapper of the character disclosed in my allowed application Serial No. 89,127, 80 filed February 18, 1926.

As the process is a continuous one, the wrappers 3, tabbed or untabbed, and preferably in stacks, are moved in succession by hand or by machine, to the point of application to the completed or assembled container or to one or more of its components. The wrappers in the stack may be as shown in Fig. 6 or 7 having notched or unnotched tab strips 3a and 3b affixed thereto by adhesive. 85 If of the form shown in Fig. 6, after removal of the individual wrapper from the stack the notches 3c are cut in the tab strip 3a to insure sharply defined, smooth corners of the wrapped container.

Prior to actual contact between the wrapper and the container, adhesive, as glue, in plastic or liquid state, is applied to container-engaging faces of the wrapper and tabs. Preferably each wrapper after removal from 100 the stack is coated with adhesive and immediately after or during the wrapper coating operation, all or certain of the tab strips 3a, 3b which are preferably coated with unset adhesive, are applied to the wrapper.

The tabs are of desired width and each is substantially symmetrically disposed with respect to the line of bending of the wrapper although if the cardboard used in the container is of considerable thickness to avoid using a tab of increased width, the longitudinal axis of the tab may be laterally displaced with respect to the line of bending.

The wrappers may be individually removed from a stack and coated in succession by an 115 adhesive-applying unit of the character described in my copending application aforesaid, or in Nitsch and Baker application No. 3,316, filed January 19, 1925, or in Nitsch and Federwitz Letters Patent No. 1,472,614.

Before setting of the adhesive as applied to the wrapper and tabs, the notches 3c are cut and the tabbed wrapper brought into registering contact with one or more of the container components at any desired stage of the packing operation described. Preferably, the article with the container elements assembled thereon, and held in position by exterior pressure, as shown in Fig. 5, is superimposed upon the coated face of the wrapper 3, the free ends 130

of the end flap 2b contacting with the middle section of the corresponding tabs 3a to effect and maintain intimate joinder of flap 2b and base 1a.

Thereupon the side panels 3d of the coated wrapper are folded into engagement with the side walls 1b of the container shell, the end sections of the tab strip 3a effecting and maintaining intimate joinder of the vertically extending edges of the side and end walls, and the tabs 3b effecting and maintaining intimate engagement of the side walls 1b and the top face 2a.

When greater strength is desirable or necessary, additional tabs may be applied to the end panels 3f as in my Letters Patent No. 1,599,500, with the further addition if desired or required of tabs extending crosswise of the wrapper blank at the line of joinder of the side and bottom panels, to reinforce all edges of the container.

Thereafter the corner lap sections 3e are folded into engagement with the end walls 2b (Fig. 10) and the end panels 3f of the wrapper wiped or folded upon the end walls and corner lap sections (Fig. 11). After the turn-in sections 3g of the wrapper are brought into engagement with the top 2a of the container (Fig. 12), the wrapping operation is completed by folding the top panel or long flap 3h of the wrapper into contact with the top face of the container and the narrow turn-in section 3g.

The adhesive wrapper at no point is in contact with the inside surface of the container but is disposed wholly exteriorly thereof which permits use of metal foil lining, or a coating of paraffin or other suitable moisture-proof material without experiencing difficulties due to lack of adhesion between elements of the wrapped container. As the container components are complementary in the sense that there is no appreciable space between nor overlapping of the walls of the formed container, the tabbed wrapper is in contact with the entire exterior surface of the container minimizing the possibility of or preventing, among other things, unintentional puncturing or tearing of the applied wrapper.

Certain steps of the method described may be effected by automatic mechanism generally of the character described in my co-pending application Serial No. 138,664, filed Sept. 30, 1926. The articles to be packed may be deposited in succession on a container element 1 and the assembly fed at right angles to conveyor mechanism by apparatus of the general nature as that utilized in my aforesaid application to feed extension or wide flange box-bottoms to a conveyor. The assembly and a wrapper then may be transported in parallel planes by the conveyor mechanism into the path of the form block of a wrapping machine as described in my aforesaid

application. After the second container element has been positioned as previously described to complete the packing of the article, the wrapping operation described may be effected by wrapping apparatus disclosed in Reifsnyder and Schwerdtle Letters Patent No. 1,152,356.

While preferably, the container consists of two pieces, rectangular in shape and forming three walls or sides as shown, either of cardboard components 1 or 2 may comprise more or less sides and the container completed by later additions held in place by the wrapper. Further, all or certain of the walls may be applied to the wrapper blank and thereafter the packing and wrapping of the article effected simultaneously.

The exact position of the tabs on the wrapper and the shape or outline of the wrapper may be changed without departing from the spirit of my invention. For example, there is disclosed in Fig. 14, a tabbed wrapper, the tab strips 4a of which are not continuous as the corresponding tab strips 3a of the wrapper previously described and the tab strips 4b are on opposite sides of the same wrapper panel. The tab strips 4a may however be continuous as in Fig. 14a. Either of the tabbed wrappers may be prepared, and after notching (Fig. 15), applied to the container or its components in any of the modes previously mentioned with respect to wrapper 3.

The outline or shape of the wrapper 4 and 4' is dissimilar from that of wrapper 3 in that whereas the latter is provided with a long flap 3h which engages three narrow turn-in sections of a side panel and the end panels, which are in engagement with the top face of the container, the panel sections of the former are each provided with two flaps 4h which engage the respective ends of the box and the end flaps of two or more of the other panel sections.

Preferably, and as illustrated, the article is packed as previously described in connection with Figs. 1 to 5, and thereafter is superimposed upon and in registration with the bottom panel wrapper-section which is disposed at the end of the wrapper blank. The lower, free end flaps 2b of the cardboard piece 2 engage the corresponding portion of the notched tab strip 4a which effects joinder of the end flaps 2a and the bottom 1b of the assembled container. The side panel 4d, the top panel 4e and the side panel 4f, successively in the order given, are brought into adhesive engagement with the corresponding faces of the assembled container, the free edge of side panel 4f preferably superposed on and overlapping the wrapper turn-in section 4g which may be folded into contact with a side wall 1b during any of the preceding steps. In any sequence, during or after the folding of the panels into contact with the container, the turn-in sections 4h of

each of the panels are folded into engagement with the end walls of the container and with certain or all of the other panels completely sealing the packed article. As in the preferred modification, the tabs are so positioned on the wrapper blank, that during the wrapping operation they effect the union of the free edges of the several wrapper components; the tabs and container may be of moisture-proof material, and the coated wrapper is disposed entirely exteriorly of the container permitting the use of metal-foil or other linings or coatings within the container or disposed on the interior surface thereof.

When greater strength is desirable or necessary, the wrapper may be provided with additional tabs to reinforce the container edges formed by the bending of the elements 1 and 2 as previously explained with respect to my preferred wrapper.

For the purpose of clearness and brevity in the appended claims, the term "complementary" as applied to the individual elements 25 of the container is used in the sense that when the container is formed therefrom there is substantially no space between nor overlapping of adjacent walls.

What I claim is:

30 1. The method of packing and wrapping an article which consists, in either sequence, of shaping container structure about the article as a form, of applying a wrapper to the container structure, and effecting union 35 of walls of the shaped container during a wrapping operation to maintain non-adhesive engagement between the container and the article enclosed thereby.

2. The method of packing and wrapping 40 articles, which comprises transporting wrappers in succession to a wrapping station, transporting to said station in succession container-forming structures and articles, applying the wrappers to container structures, at the wrapping station effecting completion of the union between adjacent, free edges of walls of the formed containers, and supporting the walls of each of the containers by non-adhesive engagement with the 50 enclosed article during a wrapping operation.

3. The method of packing and wrapping articles, which comprises transporting wrappers in succession to a wrapping station, 55 transporting to said station in succession container-forming structures and articles, at the wrapping station and during a wrapping operation, applying the wrappers to the container structures as formed on the articles, 60 completing the union between walls of the individual formed containers during a wrapping operation, and supporting the walls of each container by non-adhesive engagement with the enclosed article.

65 4. The method of packing and wrapping

articles which comprises transporting wrappers in succession to a wrapping station, transporting to said station in succession assemblies each consisting of an article and at least one of the separate components of a composite container in either sequence, bringing container components in non-adhesive engagement with an article and in container-forming position and applying in succession individual wrappers to container structures, and at said station during a wrapping operation, effecting completion of the union between adjacent, free edges of the formed containers in succession.

5. The method of packing and wrapping 80 articles which comprises transporting in succession to a wrapping station individual wrappers, each having on one face a fluid adhesive coating, transporting to said station in succession articles and container components, and at said station before material setting of the adhesive, applying in succession individual wrappers to container components supported in container-forming position by non-adhesive engagement with an 90 article.

6. The method of packing and wrapping articles which comprises transporting in succession to a wrapping station individual tabbed wrappers, each having on one face a 95 fluid adhesive coating, transporting to said station in succession articles and container components, and at said station, before material setting of the adhesive, applying individual tabbed wrappers to container components supported in container-forming position by non-adhesive engagement with an article.

7. The method of forming a wrapped container which comprises shaping a container component on or about an article to be packed 105 therein to form opposite walls and the bottom of the container, shaping a second component on or about the article to form the top and other opposite walls of the container, and applying a tabbed wrapper to said components to hold them in non-adhesive engagement with the article and to reinforce edges of the container disposed in different planes.

8. The method of producing a moisture-proof container for an article which consists of forming a container of moisture-proof material on or about the article, and effecting 115 the union of engaging walls and sealing of the container by moisture-proof strips.

9. The method of producing a wrapped container for an article, which consists of 120 assembling a plurality of separate container components on the article, holding said components in engagement with each other without overlap and in non-adhesive engagement 125 with the article, and applying a wrapper to substantially the entire exterior surface of the assembly.

10. The method of packing and wrapping 130 an article which comprises effecting non-ad-

- hesive engagement between walls of a container and the article, and applying a wrapper to the container while supporting container walls by the article.
- 5 11. The method of packing and wrapping an article which comprises in either sequence the steps of effecting non-adhesive engagement between walls of a container and the article, of effecting adhesive engagement between walls of the container and a wrapper, and thereafter, during a wrapping operation completing union of the walls by the wrapper while supporting them by the article. 70
- 10 12. The method of packing and wrapping an article which comprises effecting non-adhesive engagement between separate components of a composite container and the article, and effecting adhesive engagement between a wrapper and said components to hold the latter against said article in container-forming position. 75
- 15 13. The method of packing and wrapping an article which comprises holding components of a composite container in non-adhesive engagement with the article in container-forming position, and effecting adhesive engagement between a wrapper and said components to form a wrapped container having walls supported by the article. 80
- 20 14. The method of packing and wrapping an article which comprises effecting non-adhesive engagement between separate components of a composite container and the article, and applying a coated wrapper to said components to unite them and to hold them against the article. 85
- 25 15. The method of packing and wrapping an article which comprises holding components of a composite container in non-adhesive engagement with the article in container-forming position, and applying a coated wrapper to said components to unite them. 90
- 30 16. The method of packing and wrapping an article which comprises effecting non-adhesive engagement between walls of a container and the article, applying a tabbed wrapper to the container with tabs overlying the junction of the free edges of adjacent container walls, and supporting the container walls of the article during the wrapping operation. 95
- 35 17. The method of packing and wrapping an article which comprises effecting non-adhesive engagement between separate components of a composite container and the article, applying a tabbed wrapper to the container with tabs overlying the junction of separate components thereof, and supporting the container walls by the article during the wrapping operation. 100
- 40 18. The method of packing and wrapping an article which comprises effecting non-adhesive engagement between detached components of a composite container and the article with the edges of the components in en- 105
- 45 19. The method of packing and wrapping an article which comprises effecting non-adhesive engagement between moisture-proof, separate components of a composite container and engagement with each other without overlap, and applying a tabbed wrapper to complete the union of said components with tabs overlying the adjacent free edges thereof. 110
